DESIGN FOR A NONMETALLIC TEMPLE FOR
SPECTACLES OR SIMILAR ARTICLE

Napoleon Samuel Cabana, Attleboro, Mass., assignor to Bay State Optical Company, Attleboro, Mass., a corporation of Maine

Application November 6, 1948, Serial No. 149,493

Term of patent 14 years

(CL. D57—1)

To all whom it may concern:

Be it known that I, Napoleon Samuel Cabana, a citizen of the United States and a resident of Attleboro, in the county of Bristol, Commonwealth of Massachusetts, have invented a new, original, and ornamental Design for a Nonmetallic Temple for Spectacles or Similar Article, of which the following is a specification, reference being had to the accompanying drawing, forming a part thereof.

In the drawing.

Figure 1 is a side elevational view of a nonmetallic temple for spectacles, showing the essential features of my design in full lines; and

Figure 2 is a top plan view of the same.

I claim:

The ornamental design for a nonmetallic temple for spectacles or similar article, substantially as shown and described.

NAPOLEON SAMUEL CABANA.
